UNITED STATES PATENT OFFICE.

WESLEY R. CAMPBELL, OF PHILADELPHIA, PENNSYLVANIA, ASSIGNOR TO
GEORGE J. RICHARDSON AND EDWARD A. NOPPEL, OF SAME PLACE.

ROTARY GAS-ENGINE.

SPECIFICATION forming part of Letters Patent No. 550,742, dated December 3, 1895.

Application filed April 2, 1895. Serial No. 544,144. (No model.)

To all whom it may concern.

Be it known that I, WESLEY R. CAMPBELL, a citizen of the United States, and a resident of the city of Philadelphia and State of Pennsylvania, have invented a certain new and useful Improvement in Rotary Gas-Engines, of which the following is a full, clear, and exact description, reference being had to the accompanying drawings, forming part of this specification.

My invention relates to certain improvements in gas-engines of that class operated by the explosion of the gas, and has as its chief characteristics an evenly-balanced rotary piston having oppositely-disposed independent-valved gas-explosion chests for holding the gas under compression and to receive and direct the force of the exploded gases, as hereinafter described.

The accompanying drawings illustrate a construction embodying my invention in its preferred form.

In the drawings, Figure 1 is an elevation, partly in section, on the line 1 1, Fig. 2, of a gas-engine embodying my invention. Fig. 2 is a plan view of the same, a portion of the casing being broken away to illustrate the arrangement of the explosion-chest. Fig. 3 is a partial sectional elevation. Fig. 4 is a sectional elevation, on a somewhat larger scale, of a portion of the engine illustrated in Fig. 1. Fig. 5 is a sectional elevation showing the exploding-chamber and connections in detail. Fig. 6 is a transverse sectional elevation on the line 6 6, Fig. 3.

The engine is of the rotary type and has a rotating piston provided on its periphery with a series of inclined pockets or buckets, into which the exploded gases are forced to cause the rotation of the piston.

Referring to the drawings, A A' represent the main casing, preferably made in two sections secured together by bolts *a* and bolted to a base-plate B, which rests upon any suitable foundation. At the center of the casing are bearings for the reception of a rotating shaft D, to which is secured the piston D', which latter rotates within the casing. In the periphery of the piston are formed a large number of pockets *d*, arranged at such an angle to the circumference of the piston as will

insure the best leverage and force to be obtained from the impact of the exploded gases, the latter in practice being directed through a series of passages, each arranged on a line 55 parallel, or nearly so, to the wall of that pocket of the piston which it is designed to operate upon.

Within the main casing, at points diametrically opposite each other, are two castings E E, each casting having circular extensions in the form of trunnions *e*, which fit into correspondingly-shaped orifices formed by circular flanges *e'* in side plates F, which latter are secured by bolts *f* to the main portion of the 65 casing, the bolts *f* passing through horizontally-arranged slots *f'* in said casing, so as to permit of the movement of the side frames toward and from the central shaft D when it becomes necessary to adjust the positions of 70 the castings E E. The adjustment of these castings is effected by set-screws E², extending through the sides of the main frame and bearing upon bosses *e*², formed on the rear face of the casting at points above and below the supporting-trunnions *e*. The face *e*³ of the casting E is curved on a line corresponding to the periphery of the piston D' and fits snugly against the periphery of the piston in such manner as to prevent the escape of gases, but does not bear with sufficient force to retard the rotative movement of said piston. 75

Extending transversely through the casting E and partly through a block E' secured thereto is the exploding-chest G, communicating at one end with a valve-chamber *g* in the block E'. In this valve-chamber is a one-way valve *g'*, held to its seat by a spring *g*² and opening only in one direction to permit 80 the flow of gas and air under pressure from a pipe *h* through the valve-chamber and into the exploding-chest, the pressure of the spring being adjusted, as desired, by a nut *g*³ on the end of the valve-stem *g*⁴. At the rear end of 85 the exploding-chest is formed a valve-seat *i*, against which fits a piston-valve I, held to its seat by a spring *i'*, the rear end of which rests in a pocket-piece I', adjustably secured by bolts *i*² to the casting, so that by adjusting 90 the bolts the tension of the spring may be adjusted to permit the opening of the piston- 95 100

valve under the exercise of any predetermined pressure in the exploding-chest.

From the exploding-chest G lead two passages forming a distributing-chamber K, the 5 mouths of which are normally closed by the piston-valve I, so that no gas can enter the distributing-chamber until after the explosion of the gas in the chest G has occurred and the force of the explosion has forced back 10 the piston-valve I to open communication to the distributing-chamber. From this distributing-chamber leads a series of passages k, arranged tangentially, or nearly so, to the periphery of the rotary piston, the angle of each 15 passage, however, being different from that of each of the other passages in order that the direction of flow given to the exploded gas escaping through the passage may be on a line practically parallel to the wall of the pocket 20 of the piston against which the gas impinges. In order to decrease the area of the distributing-chamber and to provide for the adjustment of the area of the chamber, and, further, to avoid some difficulties which might be experienced in the casting of the pieces E, the 25 distributing-chambers are formed open from end to end and the openings are tapped for the reception of threaded rods or bolts l, to which are connected sliding filling-pieces l', 30 partially cut away at their inner ends, so as to but partly fill the distributing-chamber, while at the same time by turning the bolts or rods l the area of the chamber may be increased or diminished, if desired.

35 To one side of the distributing-chamber and partly surrounding the exploding-chest the casting is provided with a water-chamber E³ for the purpose of preventing excessive heating of the parts.

40 At the lower portion of the frame is a casting M, from which leads a passage m to the outer air, the mouth of the passage m being closed by a vertically-lifting valve N. At the center of the mouth of this passage m is the 45 gas-supply pipe o, the mouth of which is also closed by the central portion of the valve N, the two being so arranged with respect to each other that on the lifting of the valve both passages will be opened for the entrance of air 50 and gas to the engine. The chamber or passage m, which I term a "mixing-pot," communicates with a passage m', leading directly into a cylinder P.

In the cylinder P is a piston p, connected 55 by a rod p' with a crank p² on a stub-shaft P', secured to the main casing, the crank being secured to or forming part of a pinion Q, also mounted on said shaft. On one end of the main shaft D is a gear-wheel Q', inter- 60 meshing with and driving the pinion Q, the relative diameters of the pinion and gear-wheel being such that the pinion is rotated three times during one revolution of the gear-wheel, or, in other words, the piston p is operated three times during each revolution of the piston D'.

In the lower portion of the cylinder P is an

outlet R, in which is a one-way valve r, opening only to permit the escape of gas and air from the cylinder and normally held in a closed position by a coiled compression-spring r'. The passage R communicates with a horizontal passage R', from the opposite ends of which lead the pipes h to the two exploding-chests, so that as the piston p descends it 75 forces a quantity of mixed air and gas to both of the exploding-chambers.

The mixed air and gas are exploded in the chests G, preferably by an electric spark, two terminals x x' being placed in each chamber, 80 the terminals x being each connected to one pole of a battery X. From the opposite pole of the battery extends a wire Y to a point in close proximity to the gear-wheel Q, on which wheel are three contact-blocks Y', which successively come into contact with a contact block or brush at the end of the wire Y. From the terminals in the exploding-chambers line-wires are run to the shaft D or the gear-wheel Q', so that the circuit is completed 85 through the wheel each time one of the contact-blocks Y' makes connection with the wire Y and a spark is produced between the terminals x x' and the gas simultaneously exploded in each chamber. On one end of the 90 shaft D are secured a belt-wheel S and a balance-wheel S', preferably formed integral.

In order to govern and control the speed of the engine, I mount loosely on the shaft D a collar T, from which extend two rods t, passing through the hub of the belt-wheel S and terminating in eyes t'. In the interior of the belt-wheel are lugs u, placed diametrically opposite each other and serving as pivot-points for weighted arms U, each having a projecting finger u', engaging in the eyes t' of the rods t. As the speed of the engine increases, these weighted arms U will, of course, be forced away from each other by centrifugal force, and the fingers u', acting on the rods t, 100 will move the loose collar T toward the belt-wheel.

On the under side of the casing M is a lug u², to which is pivoted a lever U², connected at or near its opposite ends to valve-stems v v', carrying, respectively, valves V V'. The valve V is adapted to a valve-seat in a passage v², leading from the horizontal passage m' to the cylinder P and opening only in one direction, the valve being normally held closed 115 by a coiled compression-spring v³, surrounding its valve-stem v.

The valve V' is adapted to a valve-seat in a passage v⁴, leading directly from the outer air to the end of the horizontal passage m', this valve opening downwardly and being held to its seat by the spring v⁵ on the valve-stem v through the medium of the connecting-lever U². One end of the lever U² rests upon a sliding wedge w, sliding on the base-plate 125 and connected at its rear end by a rod w' to a lever W, the latter being pivoted to a lug w² on the frame and terminating in two forks w³, which embrace the collar T, being held

in contact with the collar by a coiled compression-spring w^4 , guided by a rod w^5 , which may be adjusted by nuts w^6 to increase or decrease the strength of the spring.

5 As the governor-arms U spread under the influence of centrifugal force, the collar T is moved toward the belt-wheel, and this movement is transmitted through the lever W and rod w' to the wedge w , moving the latter outward and raising the end of the lever U^2 . This movement of the lever U^2 opens the valves V V' to an extent dependent upon the movement of the wedge and permits the escape of air and gas from the cylinder P to the outer air 10 and the consequent delivery of but a small quantity of gas to the exploding-chests, reducing the force of the explosion and materially reducing the speed of the engine. In this manner the speed of the engine may be 15 governed and a constant regular speed of rotation be insured.

In order to keep the periphery of the piston clean and lubricated, I place at the bottom of the casing a wick or wiper Z, so disposed in 20 pockets z as to at all times keep in contact with the periphery of the piston, the supply of oil to keep the wick moist being added through the oil-cups z' .

In operation each revolution of the piston 25 and the consequent revolution of the gear-wheel Q' causes the pinion Q to revolve three times, and the piston p is therefore operated three times, and six explosions of gas occur during each revolution of the engine. As the 30 piston ascends, it creates a partial vacuum in the lower portion of the cylinder and in the passage m' , and the air and gas, entering the passages m and o , respectively, lift valve N and flow into passages m' , and then, raising 35 valve V, flow into the cylinder. The piston then descends and forces the mingled gas and air in the cylinder out through the pipes h to the exploding-chests G. When the piston is completely down and just ready for its 40 return movement, the valve g' being closed, one of the contact-blocks Y' completes the electric circuit and simultaneously explodes the gas in both of the chests G. The force of the explosion drives back the piston-valves I 45 against the action of the springs i' and opens communication between the exploding-chest and the distributing-chamber, when the exploded gas under extremely high pressure enters and is directed by the passages k against 50 the buckets d of the piston. The explosions and the impact of the exploded gases in the piston occurring, as they do, simultaneously in opposite directions on opposite sides of the piston counterbalance each other in such 55 manner that any strain on the shaft is avoided, although, of course, the engine could be safely operated with an exploding-chamber at but one side of the piston. The gases pass in the buckets d of the piston and are held until the 60 end of the face e^3 is passed, when they escape freely through the exhaust-ports A².

As three explosions occur in each of the ex-

ploding-chambers during each revolution of the piston, the piston is subjected to the action of six different impacts of the exploded gases and may be driven at an extremely high speed.

It will be understood that various modifications in the structure of the engine herein described may be made without departing from my invention.

Having thus described my invention, what I claim, and desire to secure by Letters Patent, is—

1. In a gas engine, the combination of a rotary piston having peripheral pockets, an exploding chest for the gases, and a valve normally closing said exploding chest, said valve being so arranged and disposed as to be opened by the force of the explosion to permit the exploded gases to escape from said chamber and act upon the peripheral pockets of the piston.

2. In a gas engine, the combination of a rotary piston having a series of peripheral pockets, an exploding chest for the gases, passages leading from said exploding chest to a point opposite the piston pockets, and a valve normally closing communication between the exploding chest and the said passages.

3. In a rotary gas engine, the combination of a rotary piston having peripheral pockets, an exploding chest for the gases, a distributing chamber communicating with the exploding chamber, means for increasing or decreasing the area of said distributing chamber, and a series of inclined passages leading from the distributing chamber to points in line with the pockets of the rotary piston, substantially as specified.

4. In a gas engine, the combination of the rotary piston having a series of peripheral pockets, an exploding chest, a distributing chamber, a valve normally closing communication between the exploding chest and the distributing chamber, and a series of pockets leading from the distributing chamber to points opposite the piston pockets.

5. The combination in a gas engine, of the rotary piston having a series of peripheral pockets, an exploding chest, a series of passages leading from the exploding chest to points opposite the pockets in the piston, and a valve located in said exploding chest and normally closing communication between the exploding chest and the gas passages, substantially as specified.

6. In a gas engine, the combination of a rotary piston having a series of peripheral pockets, an exploding chest for the gases, a spring actuated valve normally closing the escape from the said exploding chest, and a series of escape passages leading from the exploding chamber to points opposite the piston pockets, said passages being arranged tangentially, or nearly so, to the periphery of said piston, substantially as specified.

7. In a gas engine, the combination of a rotary piston having a series of peripheral pockets, exploding chests for the gases provided at

5 diametrically opposite points on the periphery of said piston, passages leading from each of said exploding chests to points opposite the piston pockets, and a valve provided in each 5 of said exploding chests normally closing communication between the exploding chest and the said passages.

8. In a gas engine, the combination of a rotary piston having a series of peripheral pockets, exploding chests for the gases arranged at diametrically opposite points on the periphery of the piston, passages leading from each of the exploding chests to points opposite the piston pockets, a pump cylinder in which the 15 air and gases are received, a piston therein, means for reciprocating the piston, two escape pipes leading from the pump cylinder and extending one to each of the exploding chests for simultaneously supplying the two exploding 20 chests and means for causing the simultaneous explosion of the gas in said chests.

9. In a gas engine, the combination of the rotary piston having a series of peripheral pockets, exploding chests provided at diametrically opposite points on the periphery of 25 said piston, valves in said exploding chests, distributing chambers in communication with said exploding chests, but normally closed by the valves, a series of inclined passages leading 30 from the distributing chambers to points opposite the piston pockets, and means for causing the simultaneous explosion of the gas in said chests, substantially as specified.

10. In a gas engine, the combination of a 35 rotary piston having a series of peripheral pockets, a movable casing, an exploding chest for the gases in said casing, passages leading from the exploding chest to points opposite the piston pockets, and means for adjusting 40 said casing toward and from the periphery of the piston, substantially as specified.

11. In a gas engine, the combination of a 45 rotary piston having a series of peripheral pockets, a movable casing, having a curved face in contact with the periphery of the piston, trunnions or supports projecting from the sides of the said casing, side supporting frames to which said trunnions are adapted, adjusting screws bearing upon the rear face of said 50 casing for moving the same toward and from the periphery of the piston, an exploding chest provided in said casing, and passages leading from said exploding chest to points opposite the pockets of the piston, substantially as 55 specified.

12. In a gas engine, the combination of a 60 rotary piston having a series of peripheral pockets, an exploding chest, a distributing chamber communicating with the exploding chest, a piston valve normally closing communication between the chest and the chamber, a spring tending to close said valve and a series of inclined passages leading from the distributing chamber to points opposite the pockets of the rotary piston, substantially as 65 specified.

13. In a gas engine, the combination of the

rotary piston, D', a series of pockets, d, formed in the periphery of said piston, a movable casing, E, having a curved face, e³, in contact with the periphery of the piston, trunnions or supports, e, projecting laterally from said casing, supporting plates, F, carrying said trunnions, securing bolts, f, adjustably securing the side plates to the main frame of the engine, adjusting screws E², bearing on the rear face of said casing, an exploding chamber, G, formed in said casing, a piston valve, I, closing the end of said exploding chamber, a spring, i', tending to hold said valve to its seat, a distributing chamber, K, a series of inclined passages, k, leading from said chamber to points opposite the pockets, d, of the piston, a gas supply pipe, h, and means for igniting the gas in the exploding chamber, substantially as specified.

14. In a gas engine, the combination of the casing, a rotary piston, D', mounted in said casing, a series of pockets, d, formed in the periphery of said piston, a movable casing, E, having one face in contact with the periphery of the piston, supporting and adjusting devices for said casing, an exploding chamber, G, formed in said casing, a piston valve, I, closing the end of said exploding chamber, a spring, i', tending to hold said valve to its seat, a distributing chamber, K, adjustable filling pieces, l', provided in said distributing chamber, adjusting bolts, l, for said filling pieces, a series of inclined passages, k, leading from said chamber to points opposite the pockets, d, of the piston, a gas supply pipe, h, and means for igniting the gas in the exploding chamber, substantially as specified.

15. In a gas engine, the combination of the rotary piston having a series of peripheral pockets, an exploding chest, passages leading therefrom to points opposite the piston pockets, entrance ports, m, and o, for the air and gas respectively, a valve, N, adapted to close both ports, a passage, m', with which said ports communicate, a pump cylinder, P, also communicating with said passage, m', a valve, V, in said passage, m', a piston, means for operating the same, an escape pipe leading from the pump cylinder to the exploding chest, and a one way valve controlling the flow of air and gas from the pump cylinder to the exploding chest, substantially as specified.

16. In a gas engine the combination of the rotary piston having a series of peripheral pockets, an exploding chest, passages leading therefrom to points opposite the piston pockets, a pump cylinder, P, having an open upper end, a piston, p, in said pump cylinder, a crank connected to said piston, gearing for revolving said crank, an entrance port, m, for the air, an entrance o, for the gas, a valve N, closing the mouths of both ports, a passage, m', leading from said ports to the pump cylinder, a one way valve, V, in said passage, m', a passage, R, leading from the pump cyl-

inder, a one way valve, r , in said passage, R , a valve chamber, g , communicating with the exploding chamber, G , a one way valve, g' , located in said valve chamber, g , and a pipe, h , extending from the passage, R , to the valve chamber, g , substantially as specified.

17. In a gas engine, the combination of the rotary piston having a series of peripheral pockets, an exploding chest, passages leading therefrom to points opposite the piston pockets, entrance ports for air and gas, a valve controlling the same, a pump cylinder, a passage leading therefrom to the entrance ports for air and gas, a piston, means for reciprocating the same, an escape pipe leading from the pump cylinder to the exploding chest, a one way valve controlling the flow of air and gas from the pump cylinder to the exploding chest, a supplemental escape passage leading from the pump cylinder, a valve in said supplemental escape passage, a governing device, and mechanism operatively connecting the governing device to the valve in said supplemental escape passage, substantially as specified.

18. The combination in a gas engine of the exploding chest, a forcing pump, an air and gas passage leading therefrom to the exploding chest, an auxiliary escape passage leading from the air and gas passage to the outer air, a valve in said escape passage, a governing device operated by the engine, said governing device being operatively connected to said valve.

19. The combination in a gas engine of the piston, the exploding chest, a pump cylinder, a piston therein, means for reciprocating the piston, entrance ports for the air and gas, a valve controlling the flow of the same, a passage extending from the air and gas ports to the pump cylinder, a valve, as V therein, an escape passage leading from the pump cylinder.

der to the exploding chest, a supplemental passage leading from the air and gas passage to the outer air, a valve as V' , in said supplemental passage, a centrally pivoted lever, U^2 , connected at one end to the stem of the valve, V' , and having its opposite end in working contact with the stem of the valve, V , a governing device operated by the engine, and mechanism connecting said governing device to the lever, U^2 , substantially as specified.

20. A governing device for gas engines comprising in combination two weighted levers or arms U , pivotally mounted at points diametrically opposite the center of rotation of the shaft of the engine, a loose collar, T , on said shaft, rods, t , connected to said sleeve, loops, t' , formed at the ends of the rods, t , fingers, U' , extending from the arms, U , into said loops, t' , a pivoted lever, W , having a bifurcated end portion embracing the collar, T , a wedge w , a connecting rod, w' , extending from the wedge to the lever, W , a pivoted lever, U^2 , resting upon said wedge, escape ports for air and gas and valves in said escape ports operatively connected to the lever, U^2 , substantially as specified.

21. In a rotary piston having a series of peripheral pockets, an exploding chest, passages leading therefrom to points opposite the pockets of the piston, a wiper or wick, Z , holding pockets, z , for holding said wiper in contact with the periphery of the piston, and oil cups, z' , supplying the lubricant to said wiper, substantially as specified.

In witness whereof I have hereunto set my hand this 14th day of March, A. D. 1895.

WESLEY R. CAMPBELL.
